LATCH MECHANISM

Alfred Peter Wehner, 4630 Dove Creek Way, Dallas, Tex.

Filed Sept. 11, 1958, Ser. No. 760,368

9 Claims. (Cl. 292—207)

The present invention relates to latches for doors, drawers and the like and more particularly to a new improved latch mechanism of simple, rugged construction and ease of operation and has for an object the provision of a child proof latch readily operated by adults.

Countless accidents occur when children obtain access to drugs, poisons and the like stored in medicine cabinets and closets.

The attempts in the past to keep drugs and dangerous instrumentalities, such as guns, from children have employed key operated locks and so called secret or hidden fasteners. While such arrangements are for the most part successful they are subject to failure unless the key is kept out of the hands of the children and the operation of the hidden or secret fastener takes place unseen by the children.

The problem of preventing small children from opening medicine cabinets is solved in accordance with the present invention by providing a simple latch of rugged construction whose operation while no mystery to the child is impossible of attainment because it requires the use of greater sustained force than the child is capable of applying.

In accordance with the present invention there is employed a release mechanism operable solely by pressure to be exerted by one finger.

More particularly and in accordance with the present invention there is provided a latch comprising a first cylindrical casing having a slot portion of which extends at least in part peripherally of the casing and having a further portion which extends toward the bottom of the casing. A second cylindrical casing is mounted coaxially with the first casing and the casings are rotatably moveable relative to each other. A drawer engaging means is secured to one of the casings and extends radially outwardly from and moveable with the casing from a drawer engaging position to a drawer disengaging position. A means including the slot is provided for locking the engaging means in the positions. The casings are also moveable axially relative to one another against force exerted by a spring to release the engaging means for movement between the positions.

For other objects of the present invention and attendant advantage thereof reference may be had to the following detailed description taken in conjunction with the accompanying drawings in which:

Fig. 1 is a top view of one embodiment of the present invention;

Fig. 2 is an enlarged cross-section of a latch embodying the present invention taken along a line substantially corresponding with line 2—2 of Fig. 1;

Fig. 3 is a perspective view of one of the casings of Fig. 2 with a portion cut away showing features of construction;

Fig. 3a is a perspective view of a modification of the casing of Fig. 3;

2

Fig. 4 is a cross-section of another modification of the present invention; and

Fig. 5 is a perspective view of a casing employed in the modification of Fig. 4.

Referring now to Fig. 1 there is illustrated a latch mechanism 10 embodying the present invention and shown in a drawer locking relation with a latching means 11 disposed adjacent drawer 12. The latch 10 is shown secured to a fixed drawer or door frame 13 of a cabinet by means of a base portion 14. In accordance with the present invention the latch mechanism may be mounted readily and with the use of the simplest tools to existing furniture without the need for boring holes or otherwise requiring the services of a cabinet maker. More particularly the latch 10 is shown secured to the frame 13 by way of wood screws 15.

The latching means 11 is rotatably moveable out of locking engagement with the drawer 12 by the application of pressure upon the top of a casing or tube 16 to release, as described in detail here-in-after, the latching means 11 for movement to a position over the base 14 and away from the drawer 12. The area of upper surface of the tube or casing 16 is purposely made small so as to limit the operation of pressure application to a single finger. For example the diameter of the upper surface preferably is no larger than one inch. While an adult is capable of applying the sustained pressure necessary to release the latch a small child is incapable of applying such force with the one finger by which the application of pressure must be exerted.

Construction details of the latch are illustrated in Fig. 2 wherein the first casing or tube 16 is shown mounted coaxially or concentrically with a second casing 17. The casings 16 and 17 are rotatably moveable relative to each other. More particularly the second casing 17 is provided with a circumferential flange 18 at its base and is held in position relative to the base 14 by way of a cooperating ring 19 secured to the base 14, for example by way of rivets 20, and having inwardly disposed flange portion 21 for engagement with the flange 18 of the casing 17.

The latching means 11 is shown forming an integral part of the casing 17. It is to be understood however that the latching means or drawer engaging arm 11 may be separately formed and secured to the casing as by way of machine screws (not shown) or by welding the engaging arm or latching means 11 to the outside surface of the casing 17. It is preferred that the latching means form an integral part of the casing for maximum strength inasmuch as it is contemplated that the drawer 12 will be vigorously drawn against the arm or latching means 11 by children attempting to open it. In this regard, in order to prevent the marring of the finish of the drawer 12, the latching means may be provided with a cushion 22 formed of rubber or other resilient material and secured in any desired manner, for example, as by way of machine screw 23, to the underside of the arm or latching means 11.

The latching means or arm 11 is maintained in either a drawer engaging position or a drawer disengaging position by a locking means comprised of several elements including a rod 24, a sleeve 25, a slot 26 formed in the casing 16 and a projection or pin 27 extending inwardly from the inner surface of the casing 17. The rod 24, shown as integral with the base 14, is provided with at least one and preferably two projections 28 extending into and otherwise received by slots 29 formed in the sleeve 25 depending from the under surface of the casing 16.

With the construction thus far described and with the parts in the position illustrated it will be apparent that the casing 16 is incapable of rotation relative to the base

14 and that its motion is limited to an axial movement relative to the casing 17 against the force of a spring 30. With the projection 27 engaging the walls of the slot 26 the latching means 11 will be locked in a drawer engaging position until such time as the casing 16 is moved axially against the force of the spring 30 to release and otherwise allow rotation of the latching means 11 to a drawer disengaging position and in a manner now to be described.

Referring now to Fig. 3 the slot 26 is shown comprised of at least three portions; a vertical portion 31 extending from the bottom of the casing 16, a horizontal portion 32 and a second vertical portion 33 at the opposite end of the horizontal portion 32. The latching means is released when the casing 16, Fig. 2, is lowered to a position wherein the horizontal portion 32 of the slot 26 is opposite projection 27. At that time the latching means 11 may be rotated freely with the projection 27 riding in the horizontal slot 32 to a position adjacent the slot 33. Now upon release of pressure from the top of the casing 16 the spring 30 will move the casing upwardly and the projection 27 will ride in the slot 33 to the lower portion thereof to lock the latching means 11 in drawer disengaging position.

The latching means 11 is moved from a drawer disengaging position to a drawer engaging position by once more applying pressure to the top surface of the casing 16 to align the projection 27 with the horizontal portion 32 of slot 26. The casing 17 now may be rotated to carry the latching means to proper locking relation with the drawer at which time the projection 27 will enter slot 31. Under influence of spring 30 the projection 27 is guided relative to casing 17 and along slot 31 to lock the latching means in a drawer engaging position.

With the latching means 11 in drawer engaging position the upward movement of casing 16, as caused by spring 30, is limited by means including a shoulder 34 at least in part peripherally formed about the bottom portion of the casing 16 and a sleeve 35 threadably mounted on the casing 17 and having an inwardly disposed flange 36 engaging the shoulder 24.

While the ring 19 mounting the casing 17 to the base 14 has been described as riveted to the base it will be understood that other means can be employed for securing the ring to the base. For example machine screws may be employed or the ring may be welded to the base. In a preferred embodiment the ring 19 is formed in two pieces in order to facilitate assembly of the latching mechanism.

A wide choice of materials known to those skilled in the art are available for construction of the latch mechanism of the present invention. The spring should be of durable spring-steel having, when formed, a compliance which will defy compression of the spring by small children seeking to release the latch. The latch of the present invention, as above described, will provide a latching means of small size and of simple operation yet will be effective to keep materials harmful to children readily accessible for considered use by adults and out of the hands of children.

Now that one embodiment has been fully described other embodiments, all within the scope of the present invention, will become apparent to those skilled in the art. For example it will be recalled that in the embodiment of Fig. 2 operation is had by depressing the casing 16 relative to casing 17 and thereafter moving the latching means 11 either into or out of engagement with the drawer 12. In Fig. 3a there is illustrated a modification in which the depression of the casing 16 automatically will rotate the latching means into and out of engagement with the drawer 12 thus providing one-finger operation of the latch. More particularly such operation is provided by providing a slot 40 in a form of helix having an open end at the bottom of a casing 16a and having a vertically depending slotted portion 41. The portion 41 func-

tions in a manner similar to the slotted portion 33 of Fig. 3 in order to provide a locking of the latching means in a drawer disengaging position. The locking of the latching means in a drawer engaging position is provided by a short portion 42 of the slot 40 being substantially vertical such that the casing 16a will have to be moved a short vertical distance before rotation of the latching means commences. In operation the depression of the casing 16a will cause the walls of slot 40 to apply a force to the projection 27, Fig. 2, which force will be translated into a rotation of the latching means as the projection 27 continues to ride along the walls of slot 40.

Yet another modification of the present invention is illustrated in Fig. 4 wherein a latching means 11b is shown forming an integral part of the first or outer casing 16b and in which the slots, which cooperate with a projection to provide the locking of the latch means in drawer engaging and drawer disengaging position, are formed in the inner casing 17b. In the modification of Fig. 4 the latching means 11b is moved from one position to another by first depressing the casing 16b against the force of the spring 30b as by applying pressure with a thumb against the concave top surface of the casing and then, after a predetermined vertical movement of the casing, by applying a rotating force with the thumb to the casing to move the latching means from one position to another. For purpose of rotating the casing with one finger, the upper concave surface of the casing may be knurled to provide a rough surface for ease of transmitting rotational motion from the finger to the casing.

One arrangement of slots suitable for use in the modification in Fig. 4 is illustrated in perspective in Fig. 5. The slots include a first vertical portion 31b, a horizontal portion 32b and, at an opposite end of the horizontal portion, a substantially vertical depending portion 33b. These slotted portions cooperate in the same manner as the portions 31-33 of Fig. 3 to provide in part a means for locking, releasing and for moving the latching means between two selected positions. More particularly the shorter slot portion 31b locks the latching means in a drawer disengaging position while the longer slotted portion 33b locks the latching means in a drawer engaging position. While both the slot 31b and 33b may be of the same size it is preferred to make the slot 33b deeper in order to require a sustained force of relatively long duration for releasing the latching means from a drawer engaging position. Thus while a child may have sufficient strength to begin release of the latch he will be unable to sustain the pressure required to complete the release of the latch from a drawer engaging position.

The additional slotted portions comprising the vertical portion 45, the horizontal slot 46 and the vertical slot 47 which extends to the top of the casing 17b are provided for the ready assembly of the component parts of the latching mechanism. In such assembly the upper or outer casing 16b is mounted over the casing 17b with the extension 27b within the slot 47. Pressure is applied to the top of the casing 16b and against the force of the spring 30b to move the extension or extending portion 27b along the slots 47, 46 and 45 to a position where the extending portion is received by the slot 31b.

While the various embodiments of the present invention have been illustrated as mounted on a frame adjacent a drawer as by way of base 14 it will be understood that when the construction of the door or drawer dictates adapters may be employed for proper mounting of the latch mechanism.

Now that the invention has been described and several modifications set forth it will be apparent that still further modifications will suggest themselves to those skilled in the art and it is intended to cover such modifications by the appended claims.

What is claimed is:

1. A latch comprising a first cylindrical casing having a slot including a portion extending at least in part pe-

ipherally thereof and having a further slotted portion extending toward the bottom of said casing, a second cylindrical casing mounted coaxially with said first casing and having a first projection extending into said slot, a base for mounting to a fixed surface adjacent the edge of a drawer, a vertically extending rod secured to said base and having a second projection intermediate its ends extending outwardly, a sleeve depending from one of said casings for receiving said rod, said sleeve having at least one vertical slot into which said second projection extends for locking said one of said casings against rotation relative to said base, the other of said casings being rotatably mounted to said base, drawer engaging means secured to said other of said casings and extending radially outward from and moveable with said other of said casings between a drawer engaging position and a drawer disengaging position, means including said first-mentioned slot and said first projection extending into said further slotted portion for locking said drawer engaging means in said positions, said casings being axially moveable relative to one another to position said first projection into said peripheral portion of said slot for releasing said drawer engaging means for movement between said positions, and a spring for normally urging said casings apart.

2. A latch as in claim 1 in which said one of said casings is provided with a shoulder portion extending at least in part around circumference thereof and in which said other of said casings is provided with an inwardly disposed flange for engagement with said shoulder portion to limit the axial movement of said one of said casings in a direction away from said base.

3. The latch of claim 1 in which said one of said casings is provided with a top surface to which force may be applied to move said one of said casings downwardly to release said drawer engaging means for movement between said positions.

4. A latch mechanism for a drawer and adapted for mounting on a surface adjacent to and fixed relative to the drawer comprising a base for mounting to the surface, an outer cylindrical casing, an inner cylindrical casing mounted in telescoping relation with said first casing and having an end extending above said first casing, one of said casings being mounted at one end thereof to said base, a drawer-front engaging arm mounted on and intermediate the ends of said outer casing, said arm being moveable about said inner casing between a drawer-engaging position and a drawer-disengaging position, means on said inner casing for locking said arm in either of said positions, and means at the top of one of said casings for moving said one of said casings downward to release said arm for movement between said positions.

5. A latch assembly for a drawer and adapted for mounting on a surface adjacent to and fixed relative to the drawer comprising a base for mounting to the

10
20
25

surface, an outer cylindrical casing mounted at one end thereof on said base, an inner cylindrical casing mounted in telescoping relation with said outer casing and having an end extending above said outer casing, a drawer-front engaging arm mounted on said outer casing and normally positioned intermediate the ends of the assembly, said arm being moveable about said inner casing between a drawer-engaging position and a drawer-disengaging position, means on said inner casing for locking said arm in either of said positions, and means at the top of said inner casing for moving said inner casing downward to release said arm for movement between said positions.

6. A latch comprising an inner cylindrical casing having a slot including a portion extending at least in part peripherally thereof and having a further slotted portion extending toward one end of said inner casing, an outer cylindrical casing mounted coaxially with said inner casing and having a projection extending into said slot, a base mounted to one end of one of said casings for securing the latch to a fixed surface adjacent a surface moveable with respect thereto, said casings being rotatably moveable relative to each other, means for engaging the moveable surface and secured to said outer casing, said engaging means being moveable with said outer casing from a moveable surface engaging position to a moveable surface disengaging position, means including said slot and said projection extending into said further slotted portion for locking said engaging means in said surface engaging position, said casings being axially moveable relative to one another to position said projection in said peripheral portion of said slot for releasing said engaging means for movement between said positions, and means normally urging said casings axially apart.

7. A latch as in claim 6 in which said slot is in part a helix and with said projection extending into said helix rotates said outer casing to move said engaging means between said positions as said inner casing is moved axially of said outer casing.

8. A latch as in claim 6 in which said outside casing is rotatably mounted to said base.

9. A latch as in claim 8 in which a helical spring within said casings provides said urging means to move said inner casing away from said base to lock said engaging means in said moveable surface engaging position.
